UNITED STATES PATENT OFFICE.

ANDREW J. DINKEL, OF CLARINDA, IOWA, ASSIGNOR TO CLARINDA LAWN MOWER COMPANY, OF CLARINDA, IOWA.

GEARING DEVICE FOR POWER WASHING-MACHINES.

1,228,887.

Specification of Letters Patent. Patented June 5, 1917.

Application filed October 12, 1915. Serial No. 55,573.

To all whom it may concern:

Be it known that I, ANDREW J. DINKEL, a citizen of the United States, and resident of Clarinda, in the county of Page and 5 State of Iowa, have invented a certain new and useful Gearing Device for Power Washing-Machines, of which the following is a specification.

The object of my invention is to provide 10 a gearing device for power washing machines.

A further object is to provide means of 15 new and novel construction whereby continuous rotary motion of one shaft imparts alternating rotary motion to another shaft.

Still a further object is to provide a support with a hinged cover and a shaft rotatably mounted in the cover and a source of power adjacent to the upper portion of the 20 support, with simple and direct gearing connections between the source of power on the support and the shaft in the hinged member.

Still a further object is to provide in such 25 a machine means for connecting the power shaft mounted on the support in operative relation with the shaft mounted on the member hinged to said support, and to provide means for connecting said hinged member whereby the hinged member may be raised or lowered without interfering with the gearing mechanism.

Still a further object is to provide such a 35 gearing device including simple means for taking up play between the gearing members.

My invention consists in the construction, arrangement and combination of the various 40 parts of the device, whereby the objects contemplated are attained, as hereinafter more fully set forth, pointed out in my claims, and illustrated in the accompanying drawings, in which:

Figure 1 shows a top or plan view of a 45 washing machine embodying my invention.

Fig. 2 shows a side elevation of the same, part of the tub and hinged cover member being shown in section.

Fig. 3 shows a vertical, sectional view 50 through the gearing mechanism.

Fig. 4 shows a horizontal, sectional view, taken on the line 4-4 of Fig. 3.

Fig. 5 shows a vertical, sectional view 55 through another portion of the gearing device, taken on the line 3-3 of Fig. 1, and

Fig. 6 shows a horizontal, sectional view, taken on the line 6-6 of Fig. 3.

In the accompanying drawings I have used the reference numeral 10 to indicate generally a support in the form of an ordinary washing machine tub, having the legs 11. The tub or support 10 has the stationary cover member 12 and the hinged cover member 13. The manner of mounting the hinged cover member upon the support 60 for pivotal movement will be hereinafter more fully described.

Mounted on the fixed cover member 12 is a bracket 14 having upwardly extending aligned bearing members 15, in which is 70 mounted a shaft 16. Mounted on the support adjacent to the bracket 14 is a supporting bracket 17, on which rests a motor 18 or other suitable source of power, having 65 the power shaft 19.

Mounted on the shaft 16 is a gear casing, the parts of which are indicated by the reference characters 20 and 21. The gear casing members 20 and 21 have bearing members 22 formed thereon to receive the shaft 80 16. On the gear casing member 20 is a laterally extending sleeve 23, which receives and is secured to one end of the bearing member 24.

The power shaft 19 extends through the 85 sleeve 24 into the lower part of the gear casing member 20, and formed on the inner end of the shaft 19 is a worm gear 25 in mesh with a gear 26 on the shaft 16.

Screwed into the gear casing member 20 90 in line with the end of the shaft 19 on which the worm gear 25 is formed, is a plug 27 having a hollow inner end in which washers 28 are received. Between the washers 28 and the end of the shaft 19 is a ball 95 29. Should the gears 25 and 26 become loose or worn, it will be seen that they may be tightened by screwing the plug 27 inwardly, or by taking it out and adding more washers 28 and then screwing it into 100 place until the parts are tight.

In this connection it may be noted that the entire motor and motor shaft may be turned pivotally on the shaft 16 until the motor is swung over the upper part of the 105 support and does not project beyond the sides thereof.

Mounted on the upper part of the gear casing 21 and communicating therewith is an ordinary grease cup 30. 110

A gear casing member 31 has formed thereon a bearing 32 for a shaft 33 arranged at right angles to the shaft 16 and extending over the hinged member 13. A 5 coaxing gear casing 34 is secured to the gear casing 31, and formed on the gear casing members 31 and 34 are bearing members 35 for the shaft 16.

On the shaft 16 is a worm gear 36 in 10 mesh with the gear 37 on the shaft 33. The worm gear 36 is fixed and the worm gear 37 is loosely mounted.

Slidably and rotatably mounted within the gear casing 31 is a clutch device comprising a collar 38 having pins 45 slidably 15 projecting toward the worm gear 37 through a collar 39 fixed on the shaft 33 and adapted in one position of the sliding movement of the collar 38 to enter openings 40 in the side of the worm gear 37.

Above the collar 38 is a grooved yoke 44 adjacent to the bearing member 32 secured to a rod 43 which receives a coil spring 42 which yieldingly tends to hold the clutch 20 member 38 in engagement with the worm gear 37. The clutch member 38 may be moved away from the worm gear 37 by means of the rod 43 slidably mounted in the gear casing member 31, having on its 25 end within the casing 31 the downwardly projecting yoke 44 with the groove over the clutch member 38, whereby the rod 43 is mounted to permit rotation of the clutch member 38 and to cause sliding movement 30 of said clutch 38 when said rod 43 is moved longitudinally.

The outer end of the rod 43 is pivoted between the arms of the yoke 46 having a suitable handle 47. The arms of the yoke 40 46 have curved faces 48 adapted to engage the gear casing member 31 so that by tilting the part 47 the rod 43 may be made to draw the clutch 38 away from the worm gear 47 for throwing the shaft 16 out of 45 gear with the shaft 33.

Mounted on the shaft 33 is a sleeve 49. The sleeve 49 and the shaft 33 project into the gear casing 50 on the central upper portion of the hinged member 13. The shaft 50 33 projects beyond the wall of the gear casing and beyond the sleeve 49, and on the projecting end of the shaft 33 is a bevel gear 51. The casing 50 has a movable cover member 52 bolted upon it. Mounted 55 on the cover member 52 and in the bottom wall of the casing 51, and supported against downward movement by the member 53, is a hollow sleeve 54 which is mounted for rotation in the gear casing and receives in it 60 slidably but non-rotatably an angular shaft 55 in the upper end of which is a head 56. On the lower end of the shaft 55 is an ordinary dolly 57.

Formed substantially midway of the 65 sleeve 54 is an annular projecting member

58 having annular slots in its upper and lower surfaces to receive the hubs of horizontal bevel gears 59 and 60 rotatably mounted on the sleeve 54. Projecting laterally from the member 58 is an arm 61 70 which forms a bearing for the rotatably mounted cylinder 62. On the cylinder 62 is a laterally extending pin 63 which travels in a horizontal elongated slot 64 in the wall of the arm 61, as shown in Figs. 3, 4 and 6. 75

Formed in the surface of the cylinder 62 are notches 65 adapted to be engaged by a pin 66 slidably mounted in an opening in the wall of the arm 61. The pin 66 is yieldingly held toward the cylinder 62 by 80 means of a spring 67, the outer end of which engages the screw plug 69 screwed into the outer end of the opening 68.

Formed on the upper surface of the cylinder 62 is a lug 70, and formed on the lower 85 surface thereof is a similar lug 71 shown in full lines in Fig. 3 and in dotted lines in Fig. 4, said lugs being curved on the surfaces farthest away from the center of the cylinder 62 and having flat edges or surfaces adjacent to the center of the cylinder 62. Said lugs 70 and 71 are arranged substantially at right angles to each other, as illustrated by the full and dotted lines in 90 Fig. 4. 95

Projecting upwardly from the bevel gears 60 is a pin 72, and projecting downwardly from the bevel gear 59 is a similar pin 73. The parts described are so arranged that when the shaft 33 is given continuous 100 rotary motion the bevel gears 59 and 60 will be rotated in opposite directions. One of the lugs 70 or 71, as for instance the lug 70, will stand out of the path of travel of the pin 73, while the lug 71 will be in the path 105 of travel of the lug 72, so that the rotation of the gear 60 will cause the pin 72 to engage the lug 71 for carrying with the pin 72 the cylinder 62, the sleeve 54 and the shaft 55, thereby rotating the dolly in one direction. 110

When the dolly has traveled for a certain distance the pin 63 engages the stop 73 projecting inwardly from the wall of the casing 50 at one side thereof, whereby the cylinder 62 is rotated a sufficient distance so 115 that the pin 73 on the bevel gear 59 will be engaged by the lug 70 as the bevel gear 59 rotates, while the lug 71 will stand in position so that it will be cleared by the pin 72. The dolly shaft 55 will then be rotated 120 in the opposite direction from that of its first rotation until the pin 63 engages the stop 74 on the interior of the casing 51 opposite the stop 73, whereby the pin 63 will be swung back to its original position and 125 the direction of the rotation of the shaft 55 will be reversed.

In completing the description of the mechanism, it may be said that the cover member 13 is mounted for hinged or pivotal 130

movement by means of brackets 75 extending upwardly and away from the member 13, having bearings 76 receiving the shaft 16. It will be seen that the cover member 13 is thereby hinged in such a way that it swings on the center of the shaft 16 so that the gears 36 and 37 are in mesh and are not interfered with by the upward swinging movement of the hinged member 13.

In the practical operation of my improved washing machine, power is supplied to the mechanism from the motor 18. The shaft 19 and the worm gear 25 transmit rotation to the gear 26 in the shaft 16, and thence through the gears 36 and 37 to the shaft 33. The bevel gear 51 on the shaft 33 rotates the gears 59 and 60 in opposite directions, thereby imparting alternating rotary motion 20 to the shaft 55 in the manner hereinbefore described. The yieldingly mounted pin 66 tends to hold the cylinder 62 in any of its adjusted positions with the point of said pin 66 inserted into one of the notches 65.

When desired the dolly shaft 55 may be disconnected from the power shaft 16 and the motor shaft by swinging the handle 47 downwardly, thereby causing the projecting ends of the yoke 46 to engage the member 32 and pull the clutch 38 out of engagement with the gear 37. By raising the handle 47 the spring 41 will be permitted to move the clutch 38 to engaging position. If it is desired the cover member 13 may be 35 raised without being interfered with by the gears of the machine. The motor 18 may be swung upwardly and over the body of the support when desired, so as to make the machine occupy a minimum of space.

I will now describe in a general way the means of connecting the shaft 16 with the wringer. Arranged at right angles and adjacent to the fixed cover member 12 is a fixed cover member 77, over which is mounted a wringer 78, having a projecting shaft member 79. The shaft 79 and the shaft 16 are operatively connected by suitable gearing devices within the gear casing 80. It will be noted that the wringer is placed at 50 right angles and adjacent to the shaft 16, so that when the hinged cover is raised it is swung back over the shaft 16, thereby allowing the operator free access to the washing machine tub from two sides. The advantage of such a general arrangement as is here set forth is obvious.

It is my intention to cover by this application any such changes of construction which may be included within the scope of 55 my claims.

I claim as my invention:

1. In a device of the class described, a support, a fixed cover member thereon, a shaft on said fixed cover member, a source of power pivotally mounted on said shaft,

and operatively connected therewith for transmitting power from the source of power to the shaft and at the same time permitting the source of power to be rotated around the shaft for a limited distance, means for connecting said shaft and said source of power including a gear casing, a power shaft mounted therein, a worm gear thereon, a gear on said first shaft, and adjustable means for longitudinally moving 75 said worm gear.

2. In a device of the class described, a support, a fixed cover member thereon, a movable cover member thereon, a shaft on said fixed cover member, a source of power 80 being pivotally mounted on said shaft, and operatively connected therewith for transmitting power from the source of power to the shaft and at the same time permitting the source of power to be rotated around 85 the shaft for a limited distance, an upright shaft in said movable member a gear casing having bearings formed thereon receiving said first shaft, and means for operatively connecting said first shaft with said upright 90 shaft whereby continuous rotary motion of the first shaft transmits alternate rotary motion to the second shaft.

3. In a device of the class described, means whereby continuous rotary motion of the 95 horizontal shaft transmits alternate rotary motion to the vertical shaft, said means comprising a gear casing, a horizontal shaft rotatably mounted therein, a bevel gear on said shaft within said casing, an upright sleeve 100 mounted in said casing, an upright shaft non-rotatably mounted in said sleeve, bevel gears rotatably mounted on said sleeve in mesh with said first bevel gear, an arm on said sleeve, a member mounted therein capable of limited rotary movement between the bevel gears on said sleeve, lugs extending upwardly and downwardly respectively from the member mounted in said arm, pins 105 on said bevel gears on said sleeve extended toward said rotary member in said arm, said lugs being so arranged that when one of the lugs is in the path of one of the pins, the other lug is not in the path of the other pin, a pin projecting from said rotary member in said arm, and opposite stop members on said casing adapted to engage said last described member.

4. In a device of the class described, a shaft, a vertical shaft means whereby continuous 120 rotary motion of the first shaft transmits alternate rotary motion to the vertical shaft, said means comprising a gear casing, in which said first shaft is rotatably mounted, a bevel gear on said first shaft within 125 said casing, a sleeve mounted in said casing, an upright shaft non-rotatably mounted in said sleeve, bevel gears rotatably mounted on said sleeve in mesh with said first bevel gear, an arm on said sleeve, a 130

member mounted therein capable of limited rotary movement between the bevel gears on said sleeve, lugs extending upwardly and downwardly respectively from the member 5 mounted in said arm, pins on said bevel gears on said sleeve extended toward said member in said arm, said lugs being so arranged that when one of the lugs is in the path of one of the pins, the other lug is not 10 in the path of the other pin, a pin projecting from said rotary member in said arm, opposite stop members on said casing adapted to engage the pins on the rotary member, and means tending to yieldingly hold 15 said rotary member in said arm against movement.

5. In a device of the class described, means whereby continuous rotary motion of a horizontal shaft transmits alternate rotary motion to a vertical shaft, said means comprising a gear casing, having said horizontal shaft rotatably mounted therein, a bevel gear on said shaft within said casing, an upright sleeve mounted in said casing, an 20 upright shaft non-rotatably mounted in said sleeve, bevel gears rotatably mounted on said sleeve in mesh with said first bevel gear, an arm on said sleeve, a member mounted therein capable of limited rotary 25 movement between the bevel gears on said sleeve, lugs extending upwardly and downwardly respectively from said member, pins on said bevel gears on said sleeve extending toward said rotary member in said arm, 30 said lugs being so arranged that when one of the lugs is in the path of one of the pins, the other lug is not in the path of the other pin, a pin projecting from said rotary member, and opposite stop members on said casing 35 adapted to engage the pin on the rotary member, said arm having portions adapted to serve as stops for limiting the movement of the projecting pin on the rotary member.

6. In a device of the class described, the 45 combination of a horizontal shaft, an upright shaft, a bevel gear on the horizontal shaft, a rotatably mounted sleeve in which said upright shaft is non-rotatably received, bevel gears rotatably mounted on said sleeve 50 in mesh with said first bevel gear, means carried by said sleeve adapted to be alternately engaged by said last described bevel gears, and means for moving said last de-

scribed means to position for alternate engagement with said last described bevel gears, whereby continuous rotary motion of 55 said horizontal shaft is imparted as alternating rotary motion to said upright shaft.

7. In a device of the class described, a support having a hinged cover member, a shaft mounted on said support, a source of 60 power mounted adjacent to said shaft on said support, means for transmitting the power from said source of power to said shaft, an upright shaft in said cover member, a horizontal shaft adjacent thereto, 65 worm gears on said first and third shafts, one of said worm gears being loosely mounted and having a clutch member formed thereon, a clutch member slidably mounted on the shaft adjacent to said last described 70 worm gear, yielding means tending to hold said last described clutch member in engagement with the clutch member formed on the worm gear, and means for moving said last described clutch member out of engagement with the worm gear and holding it in inoperative position.

8. In a device of the class described, a support having a hinged cover member, a shaft mounted on said support, a source of 80 power mounted adjacent to said shaft on said support, means for transmitting the power from said source of power to said shaft, an upright shaft in said cover member, a horizontal shaft adjacent thereto, 85 worm gears on said first and third shafts, one of said worm gears being loosely mounted and having a clutch member formed thereon, a clutch member slidably mounted on the shaft adjacent to said last 90 described worm gear, yielding means tending to hold said last described clutch member in engagement with the clutch member formed on the worm gear, means for moving said last described clutch member out of 95 engagement with the worm gear and holding it in inoperative position, and means whereby continuous rotary motion of said third shaft is imparted as alternating rotary motion to said upright shaft.
